UNITED STATES PATENT OFFICE.

FERDINAND ESPEL, OF SAN FRANCISCO, CALIFORNIA.

ICE-CREAM FREEZER.

SPECIFICATION forming part of Letters Patent No. 274,298, dated March 20, 1883.

Application filed May 24, 1882. (No model.)

To all whom it may concern:

Be it known that I, FERDINAND ESPEL, of the city and county of San Francisco, and State of California, have invented a new and Improved Ice-Cream Freezer, of which the following is a full, clear, and exact description.

My invention consists of improvements in the construction and arrangement of a horizontally-revolving cream-can, ice-barrel, and cream-beater, the barrel being mounted so as to be readily detached from the driving-gear and turned upright for opening to charge and discharge the barrel and can, and the beater being geared so as to be revolved reversely to 15 the way the can turns, as hereinafter fully described, and pointed out in the claims.

Reference is to be had to the accompanying drawings, forming part of this specification, in which similar letters of reference indicate corresponding parts in all the figures.

Figure 1 is a side elevation of my improved ice-cream freezer. Fig. 2 is an end elevation. Fig. 3 is a longitudinal sectional elevation of the ice-barrel and cream-can. Fig. 4 is a plan 25 of the cover of the ice-barrel, and Figs. 5 and 6 are details of the devices for fastening the covers of the ice-barrel and cream-can.

A represents the ice-barrel, which I prefer to make in cylindrical form, instead of the taper 30 form in which they are commonly made, because the ice can be introduced more conveniently and packs better and freezes more evenly, and it is simpler and easier to make. The said barrel is slung in a strong band, B, securely fastened to it by clips C and a bolt, D, and having trunnions E fitted in bearings F of the yoke G, by which the barrel is revolved and on which the barrel may be set upright when it is to be opened.

40 The yoke G has a journal, H, at one end, resting on the anti-friction rollers I, mounted on pivots J of the supporting-frame K. At the other end the said yoke is connected to the side of the driving-wheel L by the lugs M N and arms O, so as to be revolved thereby, the wheel being mounted on the hollow journal P of the yoke, which rests on the anti-friction rollers Q, and has a shaft, R, working in said journal to turn the beaters S of the cream-can 45 U by the shaft T, to which shaft R is coupled by a chuck, W, which slides on and off of the

square end of the beater-shaft by shifting shaft R forward and backward in said hollow journal P, said shaft R having a stop, X, dropping down in box Y, against the front end of it, 55 Figs. 1 and 2, to keep it in connection with the beater-shaft, and rising up by the stud Z to allow said shaft to slide forward through the hole a, when the beater-shaft is to be disconnected. The shaft R is geared by pinions b and d with the crank-shaft e, for turning the beaters S in the direction of arrow 1, and the barrel and can are geared with said crank-shaft by internally-toothed wheel L and pinion f, to be turned in the direction of arrow 2. 65

g represents the cover to the ice-barrel, which consists of a metal disk with a lining of wood or other non-conductor, h, secured upon the interior side by the bolts i, and the packing-gland j, which also clamps the rubber packing-ring k on the inside of the cover and presses it against the hub l of the cover m of the cream-can by bolts k', so as to pack the joint around said hub l, to prevent leakage. The cover g is clamped onto the end of the barrel, 70 with a rubber packing-ring, n, between them, by the hasps p and the catch-studs q, the hasps being pivoted to the sides of the barrel at t. The cover m is similarly clamped to the top of the can by hasps u and studs w, with a packing-ring, x, between flanges y of the cover and y' of the can, and the shaft of the beaters is packed by the washers z between collar z' and a recess of the cover; but the recess and one or more washers may be dispensed with. 85

The cream-can is supported in the horizontal position in the barrel by means of the hub l and by the feet a' at the bottom, which have suitable foot-rests between the bars b' on the inner side of the bottom b' of the barrel. 90

The shaft T of the beaters has a step-bearing in the bottom of the can at e', and said beaters have end scrapers, d', working against the bottom and cover, to keep them clear, the said scrapers being supported in the arms of the 95 beater by pins e', allowing a little play of the scrapers, and having springs f', to keep them in contact with the heads. There is also a side scraper, g', kept in contact therewith by springs h'. 100

The barrel has longitudinal ribs i' upon the inside, to keep the ice from rolling in the bar-

rel. The packing *n* between the top of the barrel and the cover *g* is confined by a wide ring, *j*, within which the cover fits, except where studs *q* rest in notches of the ring, so as not to 5 press the packing too much by the cover.

The trunnions *E* are made with large heads *l*, and inserted in band *B* from the inside, so that the heads bear against the barrel, which is recessed a little to receive them, and are 10 firmly bound by the band when it is tightened up, and are thus very substantially secured to the band.

I am aware that in ice-cream freezers a horizontally - revolving outer vessel containing a 15 can and beater the spindle of which is provided with a trunnion at its lower end, resting upon bearings attached to a longitudinal iron belt passing around the outer vessel lengthwise and upon a swinging brace, the iron belt being provided 20 at its outer end with a cross - bar, by means of which devices an upright or horizontal position can be given to the outer vessel containing the can and beater, has heretofore been employed, and therefore lay no claim to such 25 invention.

Having thus fully described my invention, what I claim as new, and desire to secure by Letters Patent, is—

1. The combination, with the supporting-frame *K*, of the revolving yoke *G*, journaled thereon, ice-barrel *A*, having band *B*, provided 30 with trunnions *E*, journaled in the bearings *F* of the yoke, cream-can *U*, arranged concentrically in the ice-barrel and revolving with it, 35 beaters *S*, arranged concentrically in the can,

and means, substantially as described, for operating the beaters and the barrel and can in opposite directions, substantially as described.

2. The combination of barrel *A*, cream-can *U*, beaters *S*, and the yoke *G*, the barrel being 40 pivoted on the yoke, the said yoke having a hollow journal, *P*, to which its driving-wheel *L* is applied, and the beater-shaft, having its driving-shaft arranged in the hollow journal *P*, substantially as described. 45

3. The combination, with the hollow journal *P* of the yoke *G*, driving-shaft *R* of the beaters, arranged in the hollow journal and adapted to slide therein, stop *X*, and chuck *W*, of the beater-shaft *T*, driving-wheel *L*, crank-shaft *e*, 50 and pinions *b d f*, substantially as described.

4. The driving-wheel *L*, mounted on hollow journal *P* of yoke *G*, and connected to said yoke by the arms *O* and lugs *M N*, substantially as described. 55

5. The packing-gland *j*, combined with packing-ring *k*, cover *g*, hub *l*, and cream-can cover *m*, substantially as described.

6. The combination, with the yoke *G*, provided with the bearings *F*, and the ice-barrel *A*, of the band *B*, clips *C*, and bolt *D*, and trunnions *E*, passing through orifices in the bolt and provided with heads *l*, substantially as described. 60
